CLAIM

The ornamental design for a spray oil bottle, as shown and described.

DESCRIPTION

FIG. 1 is a perspective view of a spray oil bottle design showing my new design.

FIG. 2 is a front view of a spray oil bottle.

FIG. 3 is a rear view of a spray oil bottle.

FIG. 4 is a left side view of a spray oil bottle.

FIG. 5 is a right side view of a spray oil bottle.

FIG. 6 is a top view of a spray oil bottle.

FIG. 7 is a bottom view of a spray oil bottle; and,

FIG. 8 is a rear side perspective view of a spray oil bottle. Any shading and cross-hatching are not features of the design but are utilized to illustrate the surface contours of the spray oil bottle design in the drawings.

The broken lines in the drawings depict portions of the spray oil bottle that form no part of the claimed design.
